UNITED STATES PATENT OFFICE.

CHARLES ESHEL SAYRE, OF PITTSBURGH, PENNSYLVANIA.

VALVE MECHANISM.

1,389,104.

Specification of Letters Patent.

Patented Aug. 30, 1921.

Application filed February 21, 1920. Serial No. 360,471.

To all whom it may concern:

Be it known that I, CHARLES ESHEL SAYRE, a citizen of the United States, residing at Pittsburgh, in the county of Allegheny and State of Pennsylvania, have invented certain new and useful Improvements in Valve Mechanism, of which the following is a specification.

This invention relates to valve mechanisms, more particularly to valve operating mechanism adapted for use in connection with life boats, and the objects of the invention are to provide a device of the character stated, in a manner as hereinafter set forth, which provides for a safe refuge boat for members of the crew or the passengers of a damaged or sinking vessel, and which embodies automatically operable elements permitting submerging and capsizing of the life boat without imperiling the lives of those abroad, thereby minimizing the loss of life concomitant to accidents of this nature.

Further objects of the invention are to provide a device of the character described, in a manner as hereinafter set forth, which is simple in its construction and arrangement, strong, durable and efficient in its use, and comparatively inexpensive to manufacture.

To the accomplishment of these and such other objects as may hereinafter appear, the invention consists of the novel construction, combination and arrangement of parts herein specifically described and illustrated in the accompanying drawing wherein is shown embodiments of the invention, but it is to be understood that the device shown is merely illustrative and that various changes in the form, proportion and minor details of construction may be resorted to, without departing from the principle or sacrificing any of the advantages of the invention, which come within the scope of the claims hereunto appended.

In the drawing forming a portion of this specification and wherein like numerals of reference designate corresponding parts throughout the several views:

Figure 1 is a sectional end view of the valve chamber having mounted therein an automatic air supply valve mechanism in accordance with the invention.

Fig. 2 is a fragmentary top view thereof, with the chamber shown in section.

Figs. 3 and 4 are end views of the operating lever and the actuating lug, respectively, with a portion of the former broken away.

Figs. 5 and 6 are top plan views of modified forms of constructions of the operating lever and associated parts.

Fig. 7 is a vertical sectional view of the device illustrating its application to a life boat.

Referring in detail to the drawing, A indicates the hull of a life boat provided with a deck 1, upon which is securely mounted, by means of the support 2, an outer housing 3 and an inner casing 4. Positioned longitudinally against the inner wall of the casing 4 is a valve casing providing a valve chamber 5, provided with an inwardly declining top portion 6. The bottom of the valve chamber 5 consists of the angularly disposed portions 7 and 8, respectively, extending toward each other, the former positioned above the latter, thereby providing an open space 9 therebetween. A partition 10 connects with the lower face of the bottom portion 8 and with the deck 1. Fixed to the lower interior portion of the valve chamber 5, are a plurality of cylindrical guide-ways 11, having open ends, and each carried by a pair of brackets 12 and 13.

As illustrated in Fig. 7, of the drawings, two complete units of valve mechanisms are shown. The two units are positioned longitudinally against the respective inner side walls of the casing 4, and separated from each other by the vertical partition B. The two units being identical in construction and operation, but one of the units will be described.

The lower edge of the housing 3 and of the casing 4 is spaced from the deck 1 to permit of the passage of the water thereunder.

Formed in the top 6, of the valve chamber 5, is the longitudinally extending air supply inlet 14, establishing communication between the valve chamber 5 and the interior of the casing 4. An elongated valve 15, adapted to seat against the valve seat 16 within the valve chamber 5, is pivotally supported at each end, as at 17, by a valve lever 18. The latter, near the central portion thereof, is fixedly mounted, as at 19, to the longitudinally extending shaft 20, which is rotatably mounted in the bearing

brackets 21 within the valve chamber 5. A counter-weight 22 is adjustably carried on the rearwardly projecting end of each of the valve levers 18 in such manner as to 5 permit the valve 15 carried on the inner ends of the valve levers 18 to slightly overbalance the counter-weights 22, and to cause the valve 15 to remain normally in the open position.

10 Mounted for vertical movement in each of the guideways 11 is a float 23, made from cork or other suitable material of equivalent buoyancy, provided with a vertically disposed connecting rod 24, which latter is 15 pivotally connected at its upper end, as at 25, to the inner end of the operating lever 26. The other end of the operating lever 26 is formed with the arms 27 and 28, forming a yoke portion through which the lever 20 is loosely mounted on the shaft 20. Mounted intermediate of the arms 27 and 28 of the yoke portion on the shaft 20, is an adjustable actuating lug 29 adapted to be fixedly secured to the shaft 20 to turn 25 therewith, by means of a set screw 30.

When the floats 23 move vertically upward on being submerged they will operate in unison to close the valve 15 as soon as the yoke portions 31 of the levers 26 engage respective actuating lugs 29 and rock the shaft 20.

Should the life boat, in connection with which the valve mechanism is adapted to be used, turn over completely in the water, 35 the valve mechanism would be upside down, but the water would enter the valve chamber 5 and act directly against the valve 15 and close same by pressure, without the use of the floats 23. Under such conditions the 40 floats 23 would not act against such closure of the valve 15, as the operating levers 26, which are actuated by said floats 23, are loosely mounted on the shaft 20 and operate to rock the latter only when moved vertically toward said valve 15, in the manner hereinbefore described. It will be noted 45 that the operation of the valve 15 is such, when in the reversed position, as to eliminate the entire weight of the floats 23 and 50 associated mechanisms, which would otherwise tend to retard and burden the closing operation of the valve 15 by the pressure of the water thereagainst. In like manner if but several of the floats 23 are 55 submerged they will operate to close the valve 15 independent of those floats which are not submerged, and such operation will not be impeded by the inaction of the floats not submerged. The guide-ways 11 are provided with lugs 32 to limit the downward 60 movement of the floats 23 therein.

The modifications in Figs. 5 and 6 show different constructions of operating levers and associated rocker members for rocking 65 the shaft 20. In Fig. 5 the lever 33 is

loosely mounted on the shaft 20 and is provided with a hub 34 having a slot 35, through which a bolt 36 is fixed in the shaft 20. In Fig. 6 the operating lever 37 is likewise loosely mounted on the shaft 20 70 and is provided with a hub 38 positioned on said shaft intermediate the arms of a substantially U-shaped rocking member 39 fixed to the shaft 20. The operation of the modified forms of construction is identical 75 to that described in connection with the preferred form.

What I claim is:

1. A valve mechanism for the purpose set forth comprising the combination with 80 means to provide an inlet and a valvular member for closing said inlet, of a rock shaft, a valve lever connecting said member with the shaft, a shaft rocking element fixed to the shaft, and a float operated operating 85 lever loosely attached to the shaft and adapted when actuated to engage said element thereby rocking the shaft and shifting the valvular member to close the inlet.

2. A valve mechanism for the purpose set 90 forth comprising the combination with means to provide an inlet and a valvular member for closing said inlet, of a rock shaft, a counter-balanced valve lever connecting said member with the shaft, a shaft 95 rocking element fixed to the shaft, and a float operated operating lever loosely attached to the shaft and adapted when actuated to engage said element thereby rocking the shaft and shifting the valvular member 100 to close the inlet.

3. A valve mechanism for the purpose set forth comprising a valve, a float, a shaft, connections between the valve and shaft to shift the valve when the shaft is rocked, 105 and means operated from the float for rocking the shaft, said means enabling the shifting of the valve independent of the rocking of the shaft by the said means.

4. A valve mechanism for the purpose set 110 forth comprising the combination with means to provide an inlet and a valvular member for closing said inlet, of a rock shaft, a valve lever having a yoke-shaped end connecting said member with the shaft, 115 a shaft rocking element fixed to the shaft, and a float operated operating lever loosely attached to the shaft and adapted when actuated to engage said element thereby rocking the shaft and shifting the valvular member 120 to close the inlet.

5. In combination, a valve chamber provided with an inlet and float guide-ways, a float operating in each of said guide-ways, a valve for closing said inlet, means for 125 limiting the movement of the floats in either direction, a rock shaft within said chamber, an actuating element for the shaft, valve levers connecting the valve with the shaft, and means connected with the floats and 130

loosely attached to the shaft for engaging said element to shift the shaft to close the valve when the floats are raised.

6. In combination, a valve chamber provided with an inlet and float guide-ways, a float operating in each of said guide-ways, a valve for closing said inlet, means for limiting the movement of the floats in either direction, a shaft within said chamber, an actuating element for the shaft, and means connected with the floats and loosely attached to the shaft for engaging said element to shift the shaft to close the valve when the floats are raised, said valve levers extending from said chamber and each having a counterweight.

7. A valve mechanism for the purpose set forth comprising a valve, a shaft, valve levers for shifting the valve, and means op-

eratively engaging with the shaft to rock the same to close the valve, the connection between said means and shaft permitting of the valve being closed independent of the rocking of the shaft by said means.

8. In combination, a valve chamber provided with an inlet and float guide-ways, a float operating in each of said guide-ways, a valve for closing said inlet, a shaft within said chamber, actuating elements on said shaft, means connecting said floats and loosely attached to said shaft for engaging said elements to shift the shaft to close said valve, each of said floats operating independently of the others and capable of shifting said shaft to close said valve.

35
In testimony whereof I affix my signature.

CHARLES ESHEL SAYRE.
